Fig. 15

FIG. 1 is a left front perspective view of an electronic thermometer showing my new design;
 FIG. 2 is a right side elevational view thereof;
 FIG. 3 is a rear elevational view thereof;
 FIG. 4 is a top plan view thereof;
 FIG. 5 is a bottom plan view thereof;
 FIG. 6 is a left front perspective view of another embodiment of my new design of FIG. 1 wherein the body portion is round in cross-section;
 FIG. 7 is a right side elevational view thereof;
 FIG. 8 is a rear elevational view thereof;
 FIG. 9 is a top plan view thereof;
 FIG. 10 is a bottom plan view thereof;
 FIG. 11 is a left front perspective view of another embodiment of my new design of FIG. 1 wherein the body portion is rectangular in cross-section;
 FIG. 12 is a right side elevational view thereof;
 FIG. 13 is a rear elevational view thereof;

FIG. 14 is a top plan view thereof; and
 FIG. 15 is a bottom plan view thereof.

I claim:
 The ornamental design for an electronic thermometer, as shown and described.
